UNITED STATES PATENT OFFICE.

JAMES J. MINICH, OF BLESSING, TEXAS.

SELF-CLEANING CURRYCOMB.

1,078,451.

Specification of Letters Patent. Patented Nov. 11, 1913.

Application filed November 16, 1912. Serial No. 731,730.

To all whom it may concern:

Be it known that I, JAMES J. MINICH, a citizen of the United States, residing at Blessing, in the county of Matagorda and State of Texas, have invented new and useful Improvements in Self-Cleaning Currycombs, of which the following is a specification.

The invention relates to curry combs and 10 more particularly to the class of self cleaning curry combs.

The primary object of the invention is the provision of a curry comb wherein the same may be readily and easily cleaned 15 without requiring the knocking of the comb against a solid structure, the scraper blades of the comb being acted upon through the medium of a cleaning plate which removes any adhering particles therefrom.

20 Another object of the invention is the provision of a curry comb in which automatic means are mounted thereon for operating the cleaner so that the scraping blade of the comb may be readily and quickly cleaned in an easy manner.

25 A further object of the invention is the provision of a curry comb of this character which is simple in construction, thoroughly reliable and efficient in operation and inexpensive in manufacture.

30 With these and other objects in view the invention consists in the construction, combination and arrangement of parts as will be hereinafter more fully described, illustrated in the accompanying drawing and 35 pointed out in the claim hereunto appended.

In the drawings:—Figure 1 is a side elevation of a curry comb constructed in accordance with the invention. Fig. 2 is a top 40 plan view thereof. Fig. 3 is a bottom plan view. Fig. 4 is a vertical longitudinal sectional view through the curry comb. Fig. 5 is an end elevation.

45 Similar reference characters indicate corresponding parts throughout the several views in the drawings.

Referring to the drawings by numerals 50 the curry comb comprises a fork arm 5 having mounted on one end thereof a handle 6 which is made fast thereto in any desirable manner and attached to the fork arm 5 are a plurality of substantially inverted U-

shaped scraper members 7 the same being arranged in spaced parallel relation to each other to provide a series of scraping blades 55 8, the members 7 being fastened to the arms 5 in any desirable manner.

Fixed in the handle 6 above the arm 5 is a resilient fork or limb 9 provided at its free ends with eyes 10 in which is loosely 60 engaged a bail 11 fixed to a cleaning plate 12 which is provided with spaced blades 8 of the members 7 while the portion of the plate 12 between the blades 8 or the slots 13 serving as cleaning bars 14 which on the 65 displacement of the plate 12 when pressing downwardly upon the resilient fork or limb 9 will scrape the blades 8 for removing particles adhering upon the blade or between the same.

70 When the pressure of the fork or limb 9 is relieved the plate is automatically shifted into normal position so that the cleaning bars 14 will lie against the closed sides of the members 7 and thereby not interfere with 75 the scraping action of the blades 8 when the curry comb is in use.

What is claimed is:—

A self-cleaning curry comb comprising a 80 rigid fork, U-shaped members arranged in spaced parallel relation and having their medial portions fixed to the said fork and forming comb teeth, a flat scraper plate having slots receiving the U-shaped members, an inverted U-shaped bail straddling the 85 fork and having its ends extended beyond the U-shaped members and fixed to the plate, a resilient member arranged above the said fork and loosely connected to the bail and movable toward and away from the fork, 90 the said bail being of a size to permit the movement of the plate outwardly to the ends of the comb teeth, and a handle united with the fork and the resilient arm, the longer edges of the slot being struck out to 95 project outwardly in convergent relation to each other at an angle to the comb teeth.

In testimony whereof I affix my signature in presence of two witnesses.

JAMES J. MINICH.
